DESIGN FOR A TOILET BOTTLE

Barbara Hurst, New York, N. Y.

Application October 31, 1936, Serial No. 65,614

Term of patent 7 years

To all whom it may concern:

Be it known that I, Barbara Hurst, a citizen of the United States of America, residing in New York city, in the county of New York, Borough of Manhattan, and State of New York, have invented a new, original, and ornamental Design for a Toilet Bottle, of which the following is a specification, reference being had to the accompanying drawing, forming a part thereof:

Figure 1 is a front view of a toilet bottle showing my new design in which the label portion is

extended to the right of the bottle solely for the purpose of clarity, said label being pendent in normal position upon the flexible cord to which it is attached to the bottle.

Figure 2 is a side view of Figure 1.

Figure 3 is a top view of Figure 1.

I claim:

The ornamental design for a toilet bottle, as shown and described.

BARBARA HURST.
